UNITED STATES PATENT OFFICE.

OSCAR W. KURTH, OF FULLERTON, NORTH DAKOTA.

DEVICE FOR RELEASING POOL-TABLE TRIANGLES.

No. 895,474.

Specification of Letters Patent.

Patented Aug. 11, 1908.

Application filed May 27, 1907. Serial No. 376,045.

To all whom it may concern:

Be it known that I, OSCAR W. KURTH, a citizen of the United States, residing at Fullerton, in the county of Dickey and State 5 of North Dakota, have invented certain new and useful Improvements in Devices for Releasing Pool-Table Triangles; and I do hereby declare the following to be a full, clear, and exact description of the invention, 10 such as will enable others skilled in the art to which it appertains to make and use the same.

My invention has for its object to provide a coin controlled device for releasing pool 15 table triangles, and to this end it consists of the novel devices and combinations of devices hereinafter described and defined in the claims.

The invention is illustrated in the accompanying drawings, wherein like characters 20 indicate like parts throughout the several views.

Referring to the drawings, Figure 1 is a view in elevation, showing a portion of an 25 ordinary pool table, and showing my improved device applied for use in connection therewith. Fig. 2 is a view partly in front elevation and partly in section, and with some parts removed, showing a device 30 for locking the triangle supporting cord against return movement. Fig. 3 is a view in front elevation, with some parts broken away and with some parts removed, showing the coin controlled mechanism for action 35 on the triangle supporting cord to hold the triangle in position above the table. Fig. 4 is a side elevation of the parts shown in Fig. 3, some parts being broken away. Fig. 5 is a view corresponding to Fig. 3, but with 40 some parts removed, and with the parts shown in different positions than in Fig. 3. Fig. 6 is a horizontal section on the line $x^6 x^6$ of Fig. 5. Fig. 7 is a horizontal section on the line $x^7 x^7$ of Fig. 5; and Fig. 8 is a 45 horizontal section on the line $x^8 x^8$ of Fig. 5.

The pool table is indicated in Fig. 1 by the numeral 1, and one wall and the ceiling of a room in which the table is placed are indicated, respectively, by the numerals 2 and 3. 50 The pool table triangle, which is indicated by the numeral 4, is suspended by a cord 5 that runs over guide sheaves 6 and 7, the former of which is applied to the ceiling at the proper point above one end of the

pool table, and the latter of which is supported from the ceiling close to the wall 2. The cord 5 is extended downward through suitable clearance passages in an upper case 8 and through suitable passages in a lower case 9, both of which cases, as shown, are 60 secured to the wall 2. The depending portion of said cord 5 is looped, and the end of said cord, as shown, is passed upward through a perforation in the bottom of said case 9 and is provided with a knot 5^a which serves 65 to anchor the said cord. A weighted sheave 10 is suspended on the depending loop of the said cord, as shown in Fig. 1.

As shown, the case 9 is provided with an upper end extension 9^a through which the 70 suspending cord 5 freely passes. This extension, however, serves no important function, but on its face it is shown as provided with a frame adapted to hold a card containing instructions as to the manner of 75 operation of the mechanism.

Rigidly secured within the case 9 is a metal framework 11, to the lower portion of which is pivotally connected a pair of opposing cord lock segments 12. These segments 12 are provided with serrated segmental edges 13 that are eccentric to the pivots of the said segments and increase their distance from said pivots in a downward direction, so that they will clamp the 85 cord when simultaneously moved upward, and will release said cord when simultaneously moved downward. By means of links 14, the lock segments are connected for simultaneous oscillatory movements, the upper ends of said links being pivotally attached to one arm of a bell crank 15 that is pivotally connected at 15^a to the frame 11. A coiled spring 16 shown as attached to one of the said segments 12 and to the upper portion of 90 the frame 11 puts both of the lock segments under tension to move upward and, hence, to clamp the cord 5 and thereby lock the same so that the engaged portion thereof can not be pulled upward, and hence the triangle 4 100 can not be pulled downward. At the free end of its upper arm, the bell crank 15 is provided with a laterally projecting stud 17 which, under downward movement, automatically engages with the hooked end 18^a 105 of a lock dog 18 that is pivotally mounted on the frame 11. The depending portion of the dog 18 is provided with a crooked cam slot 18^b

and is normally pressed against a stop pin 19 on the frame 11 by a coiled spring 20 attached to said frame and to one of the depending prongs of said dog.

5 Pivots connected to the upper left hand portion of the frame 11, as viewed in Fig. 3, is a dog tripping lever 21, the free end of which is simultaneously pressed upward by a spring 22 shown as supported by a collar 23^a on a stem 23 secured to the frame 11. The free end of this tripping lever 21 is preferably crooked, as best shown in Fig. 6, and at its intermediate portion it is provided with an eye 21^a through which the cord 5 is 10 freely passed. Just above this eye 21^a, the cord 5 is provided with a tripping collar or enlargement 5^b that is adapted to engage and press the lever 21 downward when the said sheave 10 is at its lowermost position, 15 and the triangle 4 is in its elevated position, shown in Fig. 1. To the free end portion of the trip lever 21 is pivotally connected a trip rod 24, the crooked lower end of which works in the slot 18^b of the dog 18. A light coiled 20 spring 25 attached to said trip rod and to the lever 21 yieldingly draws the depending free end of the trip rod 24 toward the left with respect to Figs. 3 and 5.

Rigidly secured to the frame 11, below the 30 bell crank 15, is a horizontally extended guide bar 26 upon which a coin receiving head 27 is mounted to slide. This head 27 is connected to the lower arm of the bell crank 15, as shown, by means of a slot and screw 35 connection 28. The head 27 carries the lower section 29 of a coin delivery chute, and this section 29 receives from an intermediate chute section 30 that is pivotally connected to lugs 31 on the uppermost or receiving 40 spout section 32, which latter is rigidly secured to the top of the case 9. The lower end of the spout section 29 is open, and when the head is moved to its extreme position toward the left as shown in Figs. 5 and 8, it 45 registers with a coin passage 33 in the guide bar 26. Below the coin passage 33 a coin receptacle 34 is shown as suitably secured within the case 9. By reference to Fig. 5 it will be noted that when the head 27 and 50 spout sections 29 and 30 are moved toward the left as shown in said view, a coin if inserted into the upper spout section 32 will be caught and held by the flaring upper end of the said spout section 30.

55 A plunger 35 works through a suitable guide in the right hand side of the case 9 and is connected to a driving head 36 which, in turn, is provided with a projecting end 37 that is adapted to engage a coin which is 60 dropped to the lower end of the spout section 29 and rests upon the guide bar 26. By reference to Fig. 4 it will be noted that one side of the lower end of the spout 29 is open so as to permit the projection 37 of the driving head to engage the coin and, hence, operate

thereon to force the head 27 toward the left. A coiled spring 38 attached to the head 36 and to one side of the case 9 yieldingly holds said head and the plunger 35 toward the right, as shown in Figs. 3 and 5.

The operation of the mechanism so far described is substantially as follows: Normally, the parts stand as shown in Figs. 1 and 3, and as already stated, the triangle 4 is locked in its elevated position by the lock segments 12. When a coin has been deposited in the lower end of the spout section 29 and the plunger 35 is forced inward, the projection 37 of the head 36 pressing against the coin forces the head 27 toward the left, thereby rocking the bell crank 15 and causing the latter, through the links 14, to move the lock segments 12 downward into releasing positions. This movement of the bell crank 15 carries the stud 17 downward into engagement with the hooked end 18^a of the lock dog 18, and the said lock dog operating on the said stud, locks the said bell crank, the head 27 and the lock segments 12 in the position shown in Fig. 5. In this position of the head 27, as soon as the plunger 35 and head 36 are permitted to return to the right, the coin will drop from the spout section 29 through the coin passage 33 and into the coin pocket 34. The cord 5 having thus been released, the 95 triangle 4 may be drawn downward and used to assemble the pool balls in the proper triangular arrangement upon the table. When the triangle is released, the weighted sheave 10 will draw the cord 5 downward and raise 100 the said triangle into the position shown in Fig. 1, and at the limit of this movement, the trip collar 5^b on the cord 5 strikes the trip lever 21 and forces the same downward from the position shown in Fig. 5 into the position shown in Fig. 3. Under this downward movement the trip lever 21 forces the laterally bent lower end of the trip rod 24 against the shoulder at the upper extremity of the slot 18^b and thereby rocks the dog 18 and causes the same to release the stud 17 of the bell crank 15, whereupon the spring 16 will 105 throw the parts 12, 15 and 27 back to their normal positions with the lock segments 12 again in engagement with the cord 5.

In connection with the mechanism described, I also preferably provide a device which, when the triangle is drawn downward into an operative position, will secure the suspending cord 5 against return movement 120 and, hence, relieve the triangle from upwardly drawing force from the weighted sheave 10. This device is placed within the upper case 8 and includes a lock segment 39 that is pivotally supported within said case 125 and is provided with a serrated segmental free edge that is eccentric to the pivot of said segment and increases its distance from said pivot in an upwardly direction. When the serrated edge of this lock segment 39 is 130

dropped against the cord 5, it presses the opposite side of the cord against a thrust block 40 secured within the case 8 (see Fig. 2).

Normally, or when the parts are in the position shown in Fig. 1, the lock segment 39 is held inoperative by a detainer afforded by a bent rod 41 which is pivotally supported at 42 and is provided with a stop shoulder 43 that engages a stud 44 on the said lock segment 39. As shown, the projecting free end of the detainer 41 is guided by a yoke 45 secured within the case 8. A coiled spring 46 attached to the lock segment 39 and to the interior of the case 8 yieldingly draws the lock segment 39 downward. A trip rod 47 is pivotally connected to the detainer 41 and is provided with an eye or coil 48 that loosely surrounds the cord 5 and is adapted to be engaged by the trip collar 5^b of the said cord 5 when the triangle is drawn down into an operative position, and the said collar is raised to its extreme position, as shown by dotted lines in Fig. 2. A light coiled spring 49 attached to the detainer 41 and to the interior of the case 8 yieldingly holds the detainer in the position shown by full lines in Fig. 2. A trip cord 50, which runs over suitable guide devices 51 from the ceiling, is attached at one end to the lock segment 39 and at its other end is shown as provided with a ball or hand-piece 52 that overlies the table 1 in a position where it may be conveniently reached.

With this device, when the triangle is drawn down into position for use, the trip collar 5^b of the cord 5 engages the looped end of the trip rod 47 and forces the detainer 41 out of engagement with the stud 44, as shown by dotted lines in Fig. 2, and this permits the lock segment 39 to fall into engagement with the cord 5 and thereby lock the same against return movement. When it is desired to return the triangle 4 to its inoperative or elevated position, it is only necessary to take hold of the hand-piece 52 and pull downward on the trip cord 50, thereby raising the lock segment 39 into an inoperative position and thereby releasing the cord 5, so that it may be drawn downward by the weighted sheave 10. When the lock segment 39 is raised into the position shown by full lines in Fig. 2, the spring 49 returns the detainer 41 to its normal position, in which position it secures the lock segment 39 in its inoperative position.

What I claim is:

55 1. The combination with a weighted cord, and a device such as a triangle suspended thereby, of coöperating lock segments having eccentric surfaces engageable with said cord to hold the same against movement, a

coöperating driving head and receiving head 60 adapted to be caused to move together, and connections from said receiving head to said lock segments for simultaneously moving the same; substantially as described.

2. The combination with a weighted cord, 65 and a device such as a triangle suspended thereby, of lock devices normally operative on said cord, a sliding head with connections for moving said lock devices into inoperative positions, means for securing said lock devices in inoperative positions, and means for raising the same to operative positions when the cord has been returned to its normal position, substantially as described.

3. The combination with a weighted cord, 75 and a triangle suspended by one end thereof, of a pair of lock segments having opposing segmental cord engaging surfaces, a bell crank, links connecting said lock segments to one arm of said bell crank, a lock dog operative on said bell crank to hold said lock segments in inoperative positions, a tripping lever with connection for releasing said dog when said lever is depressed, and a trip collar or projection on said cord operative to depress said trip lever when said cord is returned to a normal position, substantially as described.

4. The combination with a weighted cord, 90 and a triangle suspended by one end thereof, lock devices normally holding said cord against movement in one direction, means for releasing said lock devices, an independent lock device operative on said cord to hold the same against movement in the other direction, 95 and a trip device carried by said cord and operative to throw the said two classes of lock devices alternately into action, substantially as described.

5. The combination with a weighted cord, 100 and a device such as a triangle suspended thereby, of an eccentric lock segment operative to secure said cord against movement in one direction, a detainer normally holding said lock segment in an inoperative position, a trip device on said cord operative to move said detainer and release said lock segment, and a connection for moving said lock segment into an inoperative position and rendering the said detainer again operative on said lock segment, substantially as described.

In testimony whereof I affix my signature in presence of two witnesses.

OSCAR W. KURTH.
